UNITED STATES PATENT OFFICE.

JOHN J. HALLIWELL, OF TUCKAHOE, NEW YORK, ASSIGNOR TO R. HOE & CO., INC., OF NEW YORK, N. Y., A CORPORATION OF NEW YORK.

WEB-ASSOCIATING MECHANISM.

Application filed June 1, 1927. Serial No. 195,611.

This invention relates to certain improvements in associating mechanism for printing machines.

In certain classes of printing machines, as for instance newspapers or magazine presses, it may be desired to print from webs of different widths depending on the products required. Thus in printing magazines it may be desired to vary the size of the page of the product, and in newspapers it may be desired to print at one time on a web nine columns wide and at another time on a narrower web, as for instance one eight columns wide. In the production of products on such presses these webs are divided or slit and the halves or the two parts of the divided web associated in superposed relation to get the product desired. In thus associating the webs, the webs pass over certain devices known as turner-bars, by which a half or a part of the divided web is turned and brought into correct relation with the other part. Where webs of different widths are to be thus divided and associated, it has been necessary to adjust the turner bars so that the two parts of the webs will be brought into correct position. This adjustment of the bars must be very carefully done and takes up an undesirable amount of time, particularly where a quick change from one width web to another is desired.

It is the particular object of the present invention to provide an improved arrangement for associating the halves or parts of divided webs of different widths without the necessity of making any adjustments in the parts so that the press may be easily and quickly changed to print from a web of the desired width.

A further object of the invention is to produce such a construction which shall be of simple form and which can be readily and conveniently installed in the machine.

With these and other objects not specifically referred to in view, the invention consists in certain novel parts, arrangements and combinations which will be described in connection with the accompanying drawings and the novel features pointed out in the claims hereunto annexed.

In these drawings,—

Figure 1 is a diagrammatic side elevation of a printing press illustrating the invention, and

Figure 2 is a plan view of the associating

mechanism of Figure 1 looking in the direction of arrow 2 of that figure.

Referring now to these drawings, the particular machine selected to illustrate the invention is a four-color printing and perfecting machine, though it will be understood that the invention is intended for and can be used in other types of machines where it is desirable to print on webs of different widths. The web W, from a suitable source of web supply, not illustrated, is printed on one side by a pair of form cylinders 1, 2, inked by suitable inking mechanism 3, 4, and an impression cylinder 5. From this mechanism the web passes from suitable guide rolls 6 and is printed on the other side by two form cylinders 7, 8, and an impression cylinder 9, the form cylinders being inked by suitable inking mechanism 10, 11. If desired, an offset web 12 may be associated with the web to prevent offset during the second printing. From the printing couples 8, 9 the web passes over a suitable guide roll 13 to and between a pair of dividing or slitting rolls 14, 15, the slitter 16 being shown as arranged to divide the web centrally.

In accordance with the invention an improved associating mechanism is provided, whereby the divided parts or halves of the web may be associated in superposed relation, and this mechanism is so arranged that webs of different widths may have their parts so associated without requiring any adjustment of the associating mechanism. While this construction may be varied to some extent, a convenient one is that illustrated. Referring to Figure 2, there is shown a turner bar 17 and a pair of turner bars 18, 19. In Figure 2 is illustrated the lead of two webs of different widths. Referring first to the wide web W, this web is divided into two parts—W¹ and W², this web being preferably slit through the center into two equal parts, the half W¹, which in the particular construction shown is superposed on the half W², is led around the turner bar 17 and over the turner bar 18 and there associated in superposed relation with the half W². Now, assuming that the press has been employed on a narrow web X, this narrow web is divided into two parts—X¹ and X², by the slitter 16, the division being on the center line of the web. One of these parts, however, as X¹, is led around the turner bar 17 and then around the turner bar 19 and there associated in

superposed relation with the part X². It will be observed that the bars 18, 19 are so arranged with respect to each other and to the slitter that the webs come in exact position 5 for superposed relation and it is unnecessary to adjust any of the parts of the associating mechanism to obtain this desired and correct registration of the two webs. Thus a press can be very quickly changed from one size 10 product to another, which is particularly advantageous in certain newspaper work where one edition will be run on an eight column wide web and a succeeding edition on a nine column wide web.

15 It will be understood, of course, that the width of the webs referred to have been selected as merely illustrative of the invention and that the invention can be used with other width webs, and then, of course, any of the 20 bars may be made adjustable, if desired. Furthermore, it will be understood that the webs may be divided at points other than their centers for the production of desired products, the bars being correspondingly arranged to properly associate the divided parts 25 of the webs.

While the invention has been shown and described in its preferred form, it will be understood that certain variations and changes 30 may be made in the mechanisms shown and described and that such changes are within the invention as defined in these appended claims.

What I claim is:

- 35 1. In a printing machine, the combination of means for forwarding a web, means for slitting the web, means for giving one of the parts of the web a quarter turn to position it for direct association with the other part 40 of the web in superposed relation with the same side up, said other part of the web passing directly through the machine, and a second associating means cooperating with the associating means whereby the divided 45 parts of a different width web may be associated in superposed relation without adjustment of either associating means.
2. In a printing machine, the combination of means for forwarding a web, means for

slitting the web, a pair of turner bars over 50 which half of the web runs for direct association with its other half, and a third bar cooperating with one of the bars of the pair and parallel therewith for associating the two halves of a web of different width without 55 adjustment of the bars.

3. In a printing machine, the combination of means for forwarding a web, means for slitting the web into two parts, a pair of turner bars over 60 which one part of the web runs for direct association with its other part in superposed relation, and a third bar co-operating with one of the bars of the pair and parallel therewith for associating the two parts of a divided web of different width 65 without adjustment of the bars.

4. In a printing machine, the combination of means for forwarding a web, means for slitting the web centrally, a pair of turner bars over 70 which one half the web runs for direct association with its other half in superposed relation, and a third bar located at one side of the pair and parallel therewith and cooperating with one of them for associating the two halves of a divided web of different width 75 without adjustment of the bars.

5. In a printing machine, the combination of means for forwarding a web, a stationary slitter for slitting the web into two parts, a fixed means for associating the parts of the 80 web in superposed relation with the same side up, and a fixed means arranged in such relation with the associating means that the divided parts of a different width web may be directly associated in superposed relation 85 with the same side up.

6. In a printing machine, the combination of means for forwarding a web, a stationary slitter for slitting the web centrally, a pair of fixed turner bars over 90 which half the web runs for direct association with its other half in superposed relation, and a third fixed bar co-operating with one of the bars of the pair for associating the two halves of a web of different width. 95

In testimony whereof, I have hereunto set my hand.

JOHN J. HALLIWELL.
